(57) **CLAIM**

I claim the ornamental design for an interior vehicle door handle, as shown and described.

DESCRIPTION

FIG. 1 is a right front perspective view of an interior vehicle door handle showing the claimed design;

FIG. 2 is a left rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depict a boundary around the de-emphasized elements, which illustrate portions of the interior vehicle door handle which form no part of the claimed design.
